(57) **CLAIM**

The ornamental design for a carton, as shown and described.

DESCRIPTION

FIG. 1 is a perspective view of a carton showing my new design.

FIG. 2 is a front elevation view of the carton of FIG. 1.

FIG. 3 is a left elevation view of the carton of FIG. 1.

FIG. 4 is a rear elevation view of the carton of FIG. 1.

FIG. 5 is a right elevation view of the carton of FIG. 1.

FIG. 6 is a bottom plan view of the carton of FIG. 1.

FIG. 7 is a top plan view of the carton of FIG. 1.

FIG. 8 is a perspective view of the carton of FIG. 1 in a loading configuration.

FIG. 9 is a front elevation view of the carton of FIG. 1 in the loading configuration.

FIG. 10 is a left elevation view of the carton of FIG. 1 in the loading configuration.

FIG. 11 is a rear elevation view of the carton of FIG. 1 in the loading configuration.

FIG. 12 is a right elevation view of the carton of FIG. 1 in the loading configuration.

FIG. 13 is a top plan view of the carton of FIG. 1 in the loading configuration; and,

FIG. 14 is a plan view of the carton of FIG. 1 shown in an unfolded configuration.

All evenly-spaced broken lines depict environmental subject matter and do not form part of the claimed design.

1 Claim, 14 Drawing Sheets
